2 SHEETS—SHEET 2.

UNITED STATES PATENT OFFICE.

JOHN F. RUDDUCK, OF TACOMA, WASHINGTON.

NURSERY-CHAIR.

1,163,263.

Specification of Letters Patent.

Patented Dec. 7, 1915.

Application filed September 10, 1914. Serial No. 861,062.

To all whom it may concern:

Be it known that I, JOHN F. RUDDUCK, citizen of the United States, residing at Tacoma, in the county of Pierce and State of Washington, have invented certain new and useful Improvements in Nursery-Chairs, of which the following is a specification.

My invention relates to new and useful improvements in nursery chairs and aims as its principal object to construct a chair of this character in which the seat and legs are hingedly connected to the back in such manner that they may be folded flatly thereagainst when the chair is not in use so as to occupy in storage or in transit, a minimum space.

A further and more specific object of my invention is to provide a nursery chair which consists essentially in a back member, a pair of wings or legs which are hinged thereto, and a seat which is hinged to the back member and may be disposed in horizontal position between the legs or wings.

Another object is to form in the seat member an opening of such nature that the chair may be used in connection with a bed pan or vessel, in the well known manner.

A further object is to provide for the seat a cover-board which is hingedly secured and is adapted to be arranged in dependent relation to the forward edge of the seat so as to serve in connection with the leg or wing members, as a screen or housing for the vessel, or bed pan used in connection with the chair.

A still further object is to arrange the cover-board so that it may be positioned on top of the seat to cover the opening therein whereby the chair may be used in the ordinary manner. And a still further object is to provide for the chair, a lap tray which is mounted for swinging movement so that it may be disposed in horizontal position immediately over the lap of the occupant of the chair or may be swung to vertical position immediately above the back member.

The above and other incidental objects of a similar nature which will be hereinafter more specifically treated are accomplished by such means as are illustrated in the accompanying drawings, described in the following specification and then more particularly pointed out in the claims which are appended hereto and form a part of this application.

Referring now to the drawings wherein

there has been illustrated the preferred embodiment of my invention as it is reduced to practice, and throughout the several views of which similar reference numerals designate similar parts, Figure 1 is a perspective view of the chair showing the seat in a horizontal position with the cover-board in depending position, Fig. 2 is a perspective view showing the seat and cover-board in elevated position. In this figure the legs are shown in open position, Fig. 3 is a front elevation of the chair with the legs, back, and cover-board arranged against the back member, and Fig. 4 is a detail perspective view of one corner of the seat illustrating particularly, the means employed in maintaining the seat in a horizontal position.

As shown in the accompanying drawings, the preferred embodiment of my invention includes as its essential elements, a back member 10, a pair of legs or wings 11 and 12, which are hinged to the back member, a seat-board 13 which is also hinged to the back member, a cover-board 14 which is hinged to the seat-board, and a lap tray 15, which is swingingly connected to the back member.

The back member 10 is preferably formed as are the other elements of the chair, from wood, although it is quite obvious that under some circumstances, the chair may be formed of metal or any other suitable material. The back member is substantially rectangular in shape and is equipped with a pair of supporting legs 16 and 17. These members 16 and 17 are secured by screws, nails, or any other desired fastening means to the forward face of the back member and at the side edges thereof, as will be readily observed upon reference to Fig. 1. To these legs or strips 16 and 17 are hinged the leg or wing members 11 and 12, as by hinges indicated at 18. The members 11 and 12 are cut along horizontal lines intermediate their length producing the horizontal shoulders 19 which are of a length approximately equal to one-half the width of the members 10 and 11. The upper terminals of the members 10 and 11 are cut along curved lines indicated at 20 so that the seat-board supporting plates may be swung without hindrance into raised position when the seat-board is folded in the manner to be hereinafter described. If desired, the base edges of the members 10 and 11 may be cut away along curved lines as indicated at 21 although this

construction is, of course, not absolutely necessary.

- The seat-board 13 which is substantially rectangular in shape is attached to the back member 5 by a hinge rod 22, the terminals of which extend through apertures formed in the strips or back legs 16 and 17. The seat is in thickness less than one-half the width of the members 16 and 17 and the hinge rod 10 22 is spaced from the back member 10 a sufficient distance to permit the cover-board 14 to be received between the seat-board and the back member when the chair is folded.
- The cover-board is secured by a hinge 23 15 to the outer terminal of the seat-board and may, therefore, be arranged either in depending position as in Fig. 1 or in engagement with the upper face of the seat-board as in Fig. 2. When the cover-board is 20 mounted on the upper face of the seat-board it, of course, constitutes a closure for the opening 24 of the seat-board, thereby imparting to the chair a conventional appearance. It is now to be noted that when the 25 cover-board is in depending position, it forms in connection with the legs or wing members 11 and 12 a casing within which a bed pan or vessel may be positioned and concealed from view.
- 30 As a means for supporting the seat when in the position shown in Fig. 1, I employ a pair of plate members 25 and 26. These members 25 and 26 are similar in construction and are each formed from a single sheet 35 of metal which is bent along a transverse line to produce a horizontal body portion and the depending flange 27. The body portion of each plate is inserted in a kerf formed in each edge of the seat-board and 40 is secured therein by screws or any other fastening devices which may be found desirable. The flanges 27 are spaced from the adjacent edges of the seat-board such a 45 distance that the shoulders 19 of the members 11 and 12 may be received between the flanges and the adjacent edges of the seat-board. It will be readily observed upon 50 reference to the drawings, that when the seat is lowered into horizontal position, the plates 25 and 26 may be engaged with the shoulders 19 so as to support the seat and to hold the leg members against swinging movement.

Upon reference to Fig. 3, the manner in 55 which the chair is adapted to be folded will be readily observed. The cover-board is first folded to bear against the upper face of the seat-board and this latter member is then swung to engage against the forward 60 face of the back member 10. It then remains to fold one of the leg or wing members inwardly against the seat-board and to swing the other wing member into position 65 against the first member.

66 The lap tray heretofore designated as an

entirety by the numeral 15 includes a pair of parallel spaced arms 28 and 29 which are pivoted as by pins 30 to the members 16 and 17 adjacent the upper terminals thereof. A lap-board 31 is positioned between the outer 70 terminals of the arms, being secured by any suitable fastening devices. A guard rail or rim 32 is secured to the outer edge of the member 31 so that the child's food may be prevented from slipping from the lap-board. 75 In this connection, it is, of course, apparent, that the lap tray may be employed as a food tray or as a board for holding blocks or other similar toys. The tray is supported in horizontal position by the stop pins 33 80 against which the arm members bear, as shown in Fig. 1.

Having thus described my invention, what I claim and desire to secure by Letters Patent is:—

1. A nursery chair comprising a back member, side members hinged thereto, a swinging seat connected to the back member and adapted to be supported by the upper edges of the side members at the front 90 thereof, a tray, arms carrying said tray and pivoted to the back member, and lateral rests on the side members to be engaged by said arms above the points of engagement of the sides by the seat whereby the tray will be 95 supported above the seat.

2. A nursery chair comprising a back member, side members hinged thereto and having their upper portions reduced at their front edges whereby to provide horizontal 100 shoulders, a seat swingingly connected to the back member and provided with grooves in its side edges, and retainers secured in said grooves and having their free edges projected downward to engage over the shoulders 105 on the side members and bear against the outer faces of said members.

3. A nursery chair comprising a back member, rigid side members fixed to the back member, a seat swingingly mounted 110 between said fixed side members in spaced relation to the back member, side members hinged to the fixed side members, retainers on the sides of the seat at the front thereof to engage over the upper edges of the 115 hinged side members, a rigid cover-board hinged to the front edge of the seat to depend therefrom or fold over upon the same, the seat and cover-board being adapted to swing up against the back with the cover-board between the seat and the back, tray carrying arms pivoted to the back, a tray secured to said arms and stop pins on the hinged side members adapted to be engaged by the said arms and thereby support the 125 tray in spaced relation to the seat.

4. A nursery chair comprising a back, rigid side members fixed thereto, a seat disposed between said members, a pivot inserted through the seat and the fixed side mem- 130

bers, whereby the seat is mounted in spaced relation to the back, swinging side members hinged to the fixed side members, and retainers on the side of the seat at the front 5 thereof to engage over the upper edges of the swinging side members.

In testimony whereof I affix my signature in presence of two witnesses.
